VENETIAN BLIND

Walter J. Stuber, Philadelphia, Pa., assignor to
 Carey-McFall Company, Philadelphia, Pa., a
 corporation of Pennsylvania

Application March 6, 1940, Serial No. 322,604

5 Claims. (Cl. 156—17)

This invention relates to the slat-tilting mechanisms of Venetian blinds. Venetian blinds, in addition to being made to various lengths and widths to fit windows of various dimensions, are produced in three standard slat widths, namely; narrow, medium, or wide, to suit the tastes of different purchasers. Normally, a different head casing, head rail, and slat tilting mechanism is required for each different slat width.

The object of the present invention is to provide a single tilting mechanism, head rail and head casing which will accommodate any one of the three different slat widths, without change.

The construction and operation of the tilting mechanism constituting the subject matter of the present invention will be fully disclosed hereinafter, reference being had to the accompanying drawings, of which:

Fig. 1 is a front elevation of the blind with the top and front plates of the head casing removed, and with a portion of the head rail shown in section, for the purpose of clarity;

Fig. 2 is a transverse section taken on the line 2—2, Fig. 1;

Fig. 3 is a transverse section taken on the line 3—3, Fig. 1;

Figs. 4, 5 and 6 are transverse sections similar to Fig. 3; and

Figs. 7 and 8 are detached perspective views of parts of the tilting mechanism.

The head casing is fully shown and described in a divisional application, which resulted in the issuance of United States Patent No. 2,220,796, dated November 5, 1940.

As shown in said patent, and in Fig. 1 of the present case, the head casing A includes a pair of end brackets 1, 1, each of which is provided with a bottom horizontal flange 4 for supporting the opposite ends respectively of the head rail 10. The head rail 10 is of angular cross-sectional construction and includes a horizontal bottom plate 12 on which is mounted the tilting mechanism of the blind.

The blind, as usual, includes laterally spaced ladder tapes which support the slats and the bottom rail of the blind, and elevating cords with suitable locking mechanism for securing the slats at any desired elevation.

The cord-locking mechanism is fully shown and described in a copending divisional application Serial No. 342,345, filed June 25, 1940.

The bottom plate 12 of the head rail 10 inwardly from each of the opposite ends thereof, is provided with laterally elongated front slots 43 and corresponding lateral elongated back slots 55

44 of a length to accommodate the width of the front and back tapes 46 and 47 respectively of the ladder tapes 45, 45 of the blind. Intermediate the slots 43 and 44 solid portions 48 of the bottom plate 12 support U shaped brackets 50 (Fig. 8). The upper end of each leg of the U shaped bracket 50 is bent in the form of a segment of a circle about a common center x, the outer surfaces of said segments being adapted to be engaged respectively by the tapes 46 and 47 of the ladder tapes 45. The upper ends of the ladder tapes 46 and 47 pass through slots 53 and 54 of rocker elements 55, each of which is provided with end arms 56 extending inwardly from the opposite ends respectively of the body plate 57 of the rocker 55 in which the tape slots 53 and 54 are formed. Coincidental with the center x the arms 56, 56 are provided with square openings 58, 58 for the reception of a tilt shaft 60.

The opposite ends of the tilt shaft 60 are indirectly supported by brackets 61 and 62 secured to and projecting upwardly from the bottom plate 12 of the head rail 10. Intermediate its opposite ends the tilt shaft 60 is supported by a bracket 63, as shown in Figs. 1 and 3, said bracket 63 being secured to the bottom plate 12 of the head rail 10 and having a U shaped opening 64 formed therein for reception and support of the shaft 60.

Rotatably mounted in the bracket 61 is a worm 66 which is secured to a shaft 67 supported by bearings 68, 68 carried by the bracket 61. On the outer end of the shaft 67 is a rope or ball chain sheave 69 in the peripheral grooved edge of which is mounted a tilting rope or chain 70. The worm 66 intermeshes with the teeth 71 of a worm wheel segment 72 which is pivotally mounted on a stud 75 secured to the bracket 61 with its axis axially aligned with the center x, which also is or coincides with the longitudinal axis of the tilt shaft 60. Above the pivot 75 the worm wheel segment 72 is provided with a lateral extension 76 which is, in turn, provided with a depending portion 77 having a square opening 78 for removably receiving and supporting the one end of the tilt shaft 60. Slidably mounted in the opposite end of the hollow square shaft 60 is a trunnion 80, which may be moved axially of and within the hollow square shaft 60. The trunnion 80 is adapted to be projected into a bearing opening formed in one wall 81 of a U shaped housing 82, which is secured to the bracket 62, said trunnion being provided with a collar 83 which limits its outward movement with

respect to the square shaft 60. A cotter-pin 84 passing transversely through the square shaft 60 forms an abutment for the inner end of the trunnion 80 for retaining said trunnion in pivotal engagement with the housing 82.

The cotter pin 84 may be readily removed from the shaft 60 to permit the trunnion 80 to be moved axially into said shaft to release the outer end of the trunnion from its bearing opening in the housing 82, whereupon said shaft may be moved axially to remove its opposite end from the supporting section 77 in the worm wheel 72, the supporting section 77 in the worm wheel 72, whereupon the shaft 60 with the rockers 55, 55 thereon may be raised upwardly out of the U shaped bearing opening 64 in the bracket 63 and through the openings 85 formed between the ends of the segmental extensions 51 and 52 of the legs of the U shaped brackets 50. This construction provides for readily assembling and disassembling of the tilt shaft with respect to the head rail. The rockers 55, 55 are slideable with respect to and axially of the square shaft 60 with the legs 56, 56 of each rocker disposed at the opposite ends respectively of the brackets 50, the brackets 50 maintaining alignment of the rockers with the tape openings 43 and 44 in the bottom plate 12 of the head rail 10 for further facilitating assembling and disassembling of the elements while insuring proper alignment of the rockers with the tape openings during operation of the blind.

Normally Venetian blinds for general use are made with slats of three different widths, for example, some blinds are provided with slats having a width of $1\frac{3}{4}$ inches, others with slats $2\frac{1}{8}$ inches wide, while others are provided with slats $2\frac{3}{8}$ inches wide. These dimensions are given as a matter of example and are not to be considered as placing any limitation on the size of slats which may be used with the structure of the present blind. Heretofore it has been customary to provide head rails, casings, and tilting mechanism of three different sizes to agree respectively with the different sizes of slats to be used. This required different dies, etc. for manufacturing the elements of different sizes. The present invention makes it possible to use any one of the three different sized slats with one and the same size of head structure, whereby but one size of head structure is all that is necessary to make and maintain in stock, which is a material advantage to the manufacturer as well as the jobber and retailer, which latter may keep in stock slats of the different sizes to be employed with the head structure of but one size.

As a matter of illustration, Figs. 3 and 4 illustrate the use of the $1\frac{3}{4}$ inch slats and show the blind in the maximum open and maximum closed position, i. e. with the slats of Fig. 3 in a horizontal or open position, while Fig. 4 illustrates the tilting mechanism as having been operated to tilt the slats into the fully closed position. Fig. 5 shows a blind with the smallest sized slats in the fully open position, while Fig. 6 illustrates the narrow slats in the fully closed position with the tilting mechanism having been operated to the same extent as the tilting mechanism in Fig. 4.

As shown in Figs. 3, 4, 5 and 6 the tapes 46 and 47 in extending from the uppermost slat of the blind through the slots 43 and 44 to the rocker 55 bear against the outer surfaces of the segmental ends 51 and 52 of the brackets 50 as shown in Figs. 3 and 5. When the shaft 60 is rocked by operation of the tilt rope or chain 70

the rockers 53 pivot about the center x and release one of the tapes 46 or 47, as the case may be, completely from the segment 51 or 52, as the case may be, leaving said tape slack and thereby permitting the edges of the slats adjacent said tape to drop freely, as shown in Figs. 4 and 6, while the opposite tape 46 or 47, as the case may be, is drawn around the segment against which it normally rests, across the opening 85 between the ends of the segments 51 and 52, and into contact with and around the second segment, thereby pulling upwardly on that particular tape and causing the edges of the slats lying adjacent thereto to be raised as shown in Figs. 4 and 6. The substantially complete circle provided by the segments 51 and 52 compensates for the difference in widths of the slats and makes it possible to use one size of rocker for any of the different sizes of slats that may be desired and requires but a slight difference in degree of rocking of the shaft 60 to bring the slats of any of the different sizes from the fully opened to the fully closed position.

The lower ends of the ladder tapes 45, 45 are secured to a bottom rail 90 in the usual manner and the slats 91, 91 are supported in spaced relation to each other along the tapes 45, 45 by the usual cross tapes 92. Each slat 91 is provided with a transverse slot 93 for passage of an elevating cord 94 which, as usual, is also secured at one of its ends to the bottom rail 90. The elevating cords 94 pass upwardly through the slots 93 in the slats 91 substantially midway between the opposite longitudinal edges of the ladder tapes 45 to be substantially hidden from view by said ladder tapes. The elevating cords 94 then pass upwardly through aligned openings 96 and 97 formed in the solid portions 48 of the bottom plate 12 of the head rail 10 and the base portion 98 of each bracket 50 to a roller or wheel 99 which is rotatably mounted between the legs of the U shaped brackets 50, as clearly shown in Figs. 1, 3, 4, 5 and 6. From the rollers 99 the elevating cords 94 pass horizontally to and under a roller 100 which is rotatably mounted in a housing 82 carried by the bracket 62. From the roller 100 the elevating cords pass through the locking mechanism, below which the cords 94 are joined the periphery of a roller 101 which is rotatably mounted on a shaft 102 having its ends secured in extensions or legs 103 of a U shaped bracket 104 carried by the bracket 62. From the roller 101 the cords 94, 94 extend downwardly through an opening 105 formed in the bottom plate 12 of the head rail 10 to be joined together at their lower ends in a common tassel or handle 106, whereby raising and lowering of said tassel will effect corresponding lowering and raising of the bottom rail 90 and the slats 91.

I claim:

1. A Venetian blind comprising a tilt shaft, rockers in axially spaced relation on said shaft, each rocker comprising a ladder tape attachment plate spaced radially from said shaft with its longitudinal axis parallel to said shaft axis, said tapes being connected to said plate on lines parallel to and spaced laterally from said plate axis, a pair of supporting arms for each attachment plate mounted on said shaft in axially spaced relation to each other, and a fixed ladder tape guide between each said pair of arms and comprising a substantially cylindrical portion approximately concentric to said shaft axis and having a diameter greater than said lateral spacing of said tape connections.

2. A Venetian blind comprising a tilt shaft, rockers in axially spaced relation on said shaft, each rocker comprising a ladder tape attachment plate spaced radially from said shaft with its longitudinal axis parallel to said shaft axis, said tapes being connected to said plate on lines parallel to and spaced laterally from said plate axis, a pair of supporting arms for each attachment plate mounted on said shaft in axially spaced relation to each other, a fixed ladder tape guide between each said pair of arms and comprising a substantially cylindrical portion approximately concentric to said shaft axis and having a diameter greater than said lateral spacing of said tape connections, and leg portions below said cylindrical portion, and slat elevating rope pulleys rotatably mounted between said leg portions below said tilt shaft.

3. A Venetian blind comprising a head rail, brackets carried by said head rail, a tilt shaft removably supported by said brackets, rockers in axially spaced relation on said shaft, each rocker comprising a ladder tape attachment plate spaced radially from said shaft with its longitudinal axis parallel to said shaft axis, said tapes being connected to said plate on lines parallel to and spaced laterally from said plate axis, a pair of supporting arms for each attachment plate mounted on said shaft in axially spaced relation to each other, a fixed ladder tape guide between each said pair of arms and comprising a substantially cylindrical portion approximately concentric to said shaft axis and having a diameter greater than said lateral spacing of said tape connections, and leg portions below said cylindrical portion, and slat elevating rope pulleys rotatably mounted between said leg portions below said tilt shaft and secured to said head rail, said head rail being slotted at each side of said leg portion from said leg portions outwardly to an extent at least as great as the diameter of said cylindrical portion for passage of said ladder tapes through said head rail.

4. A Venetian blind comprising a head rail, brackets carried by said head rail, a tilt shaft re- 45

movably supported by said brackets, rockers in axially spaced relation on said shaft, each rocker comprising a ladder tape attachment plate spaced radially from said shaft with its longitudinal axis parallel to said shaft axis, said tapes being connected to said plate on lines parallel to and spaced laterally from said plate axis, a pair of supporting arms for each attachment plate mounted on said shaft in axially spaced relation to each other, a fixed ladder tape guide between each said pair of arms and comprising a substantially cylindrical portion approximately concentric to said shaft axis and having a diameter greater than said lateral spacing of said tape connections, and leg portions below said cylindrical portion secured to said head rail, said cylindrical portion being slotted in its upper side to permit passage of said shaft when being removed from and replaced in its said supporting brackets.

5. A Venetian blind comprising a head rail, brackets carried by said head rail, a tilt shaft removably supported by said brackets, rockers in axially spaced relation on said shaft, each rocker comprising a ladder tape attachment plate spaced radially from said shaft with its longitudinal axis parallel to said shaft axis, said tapes being connected to said plate on lines parallel to and spaced laterally from said plate axis, a pair of supporting arms for each attachment plate mounted on said shaft in axially spaced relation to each other, a fixed ladder tape guide between each said pair of arms and comprising a substantially cylindrical portion approximately concentric to said shaft axis and having a diameter greater than said lateral spacing of said tape connections, and leg portions below said cylindrical portion secured to said head rail, said cylindrical portion being slotted in its upper side to permit passage of said shaft when being removed from and replaced in its said supporting brackets, said rocker arms being splined to said tilt shaft and movable axially therealong for automatically aligning said rockers with said fixed guides during replacement of said shaft in its said supporting brackets.

WALTER J. STUBER.
